UNITED STATES PATENT OFFICE.

CHARLES RALPH BOSHART, OF LOWVILLE, NEW YORK.

ANIMAL TAG.

Application filed September 19, 1925. Serial No. 57,325

Generically, this invention relates to tags, but it more especially comprehends the type adapted to be directly attached to animals for purposes of identification.

5 An important object of this invention is the provision of a tag adapted to pierce and be secured to the ear or other portion of the body of an animal in such a manner as to give little discomfort and with slight possibility of being disengaged from its normal position.

Another important object of this invention is the provision of means for sealing the tag in its normal position, said seal adapted 15 to bear certain distinguishing insignia, so as to render removal of or transfer of the tag from one animal to another impossible without breaking the seal.

Other important objects of this invention 20 are: to provide a tag having means for piercing or perforating the ear or other portion of the animal and when operatively positioned adapted to secure a member on either side of the ear or other portion, means 25 adapted to extend through the first mentioned means to strengthen and seal the same against unauthorized removal; both the tag and seal adapted to be expeditiously positioned, the composite tag being simple in 30 construction, economical to manufacture, and efficient for the purposes intended.

With these and other objects in view, which will become apparent as the description proceeds, the invention resides in the 35 construction, combination and arrangement of parts, hereinafter more fully described and claimed, and illustrated in the accompanying drawings, in which like characters of reference indicate like parts throughout 40 the several figures, of which:

Fig. 1 is a perspective view of my tag showing the hollow rivet member;

Fig. 2 is a longitudinal section of Fig. 1;

Fig. 3 is a cross section of the seal bolt;

45 Fig. 4 is a top plan view of the tag and metal seal bearing the insignia; Fig. 4^a is a longitudinal section showing hollow rivet clinched in position with seal bolt operatively positioned and riveted; and Fig. 4^b is 50 a bottom plan view of seal bolt riveted with impression;

Fig. 5 is a sectional view of a modified form showing the parts in relative disassembled position; and Fig. 5^a is a side elevation

of the parts assembled with the seal bolt in 55 riveted position; and

Fig. 6 is a longitudinal sectional view of a further modification showing one rivet in place and crimped with seal bolt therein and riveted, and other rivet in place before 60 crimping.

The animal tags now in use and with which I am familiar have proven deficient in being easily dislodged by being caught on objects, etc., and likewise, with little difficulty transferable from one animal to another by irresponsible parties; and it was to overcome such deficiencies, and to provide a tag that would be strong, smooth, durable, easily, firmly and permanently attached to the ears or flesh of an animal, and having means for sealing the same to prevent its removal from one animal to another, such seal constituting a metal seal bolt for strengthening the device and presenting upon its head and riveted end sufficient surface for impressions of letters, numbers or insignia desired by certain companies, corporations, municipalities, counties, States, governments, etc., for the detection of fraud and tracing or identification of certain animals, that I designed the composite tag and seal forming the subject matter of this invention.

In the illustrated embodiment characterizing this invention there is shown a tag A 85 formed from one piece of material folded upon itself to form the substantially parallel arms or members 1 and 2, respectively, the free end of arm 1 being preferably formed with an integral right angularly 90 downwardly extending rivet-like lug or extension 3 formed with a central bore 4 and having its lower end beveled as at 5 to provide a sharp cutting edge 6 for a purpose which will hereinafter more fully appear. 95 While I have preferably shown the rivet member 3 as integral with arm 1, it is often desirable to form the same separately to be riveted to the arm as desired.

The lower arm 2 is formed with an opening 7 slightly spaced from its free extremity through which is adapted to extend the rivet extension 3 when the tag is operatively positioned. The said opening 7 is countersunk or beveled as at 8, which not only aids 100 in guiding the rivet member 3 through said opening 7 but co-operates with the cutting edge 6 to remove a disc of flesh from the 105

ear or other portion of the animal when the tag is properly positioned and pressure is exerted upon the said arms 1 and 2 in meeting direction. When the arms have been brought into substantial parallelism the end of member 3 extends through and beyond the opening 7 and is crimped by a suitable tool or otherwise riveted, thereby securely fastening the tag to the animal.

10 In order to additionally strengthen the securing means and to further insure the tag against being broken loose and lost, and, especially, to prevent its being transferred from one animal to another, I provide a 15 metal seal bolt 9 formed with a head 10 adapted to bear certain numbers, letters or insignia 11, and though the free end adapted to be crimped or riveted by a proper impression bearing tool after it has been inserted 20 through opening 4, may be solid, in the present instance it is countersunk as at 12 and crimped or riveted as at 13 presenting the desired impression 14, as clearly shown in Fig. 4^b of the drawings.

25 In Fig. 5 is illustrated a modification similar in construction and operation to that above described, except the arms 1 and 2 are cut intermediate their length slightly spaced from the rivet member 3 to form, respectively, button or disc members 1' and 2', in all other respects being identical to Figs. 1, 2, 3, and 4. Of course, it is understood 30 that the members 1' and 2' may be initially so formed if desired.

35 In Fig. 6 is illustrated a still further modification similar in construction and operation to the forms above described except, it is adapted to pierce the ear or other portion of the animal in two places instead of 40 one, and comprises an upper plate 1" formed with a rivet member 3" slightly spaced inwardly from each end of the said plate, said rivet members adapted to extend through registering openings 7" and be 45 crimped or riveted on the member 2", corresponding to the similar operations in the above forms. The seal rivet 9 is adapted to extend through each of the members 3" in a similar manner and for the same purpose

as in the forms heretofore described, as 50 clearly shown in Figs. 4 and 6.

From the above it is apparent that I have 55 designed a seal-tag of great adaptability, easily attached to an animal and sealed, simple in construction, economically manufactured, and efficient for the purposes intended.

Although in practice, I have found that the form of my invention illustrated in the 60 accompanying drawings and referred to in the above description as the preferred embodiment, is the most efficient and practical; yet realizing the conditions concurrent with the adoption of my device will necessarily 65 vary, I desire to emphasize that various minor changes in details of construction, proportion and arrangements of parts, may be resorted to within the scope of the appended claim without departing from or 70 sacrificing any of the principles of this invention.

Having thus described my invention, what I desire protected by Letters Patent is as set forth in the following claim:

An animal marker comprising a flexible 75 element bent intermediate its ends to form upper and lower members to provide a loop, the free extremity of the upper members being formed with an opening, a sleeve 80 of uniform diameter surrounding said opening and extending therefrom, the free extremity of the lower member being formed with an opening through which said sleeve 85 is adapted to project and sufficiently beyond the exterior surface thereof for crimping purposes, a seal embodying a head and a shank, the head being adapted to contact the exterior surface of the upper member 90 and the shank extending through the sleeve and the opening in the lower member to the exterior thereof, the free end of the shank being formed with a head of sufficient diameter to overlie the crimped end of said sleeve, said head cooperating therewith to 95 maintain the upper and lower members in interlocked parallel relation.

CHARLES RALPH BOSHART.
